UNITED STATES PATENT OFFICE.

ROBERT A. WALKER, OF DES MOINES, IOWA.

ADJUSTABLE JOINT LOCKING DEVICE.

1,322,850.

Specification of Letters Patent. Patented Nov. 25, 1919.

Application filed January 16, 1918. Serial No. 212,136.

To all whom it may concern:

Be it known that I, ROBERT A. WALKER, a citizen of the United States, residing at 1339 West 12th street, in the city of Des Moines, 5 county of Polk, and State of Iowa, have invented a new and useful Adjustable Joint Locking Device, of which the following is a specification.

My invention relates to an adjustable locking device for effecting a joint between conduit sections, such as stack sections.

An important object of the invention is to provide a device of the above mentioned character, which is of simple construction, 15 cheap to manufacture, and capable of a large range of adjustment.

In the accompanying drawings forming a part of this specification and in which like numerals are employed to designate like 20 parts throughout the same,

Figure 1 is a side elevation of a device embodying my invention,

Fig. 2 is a longitudinal section taken on line 2—2 of Fig. 1, and,

Fig. 3 is a transverse section taken on line 25 3—3 of Fig. 1.

In the drawings, the numeral 1 designates a conduit or stack section, which is double walled, and adapted to telescope within an 30 upper stack or conduit section 2, which is also double walled.

The lower inner conduit section 1 is provided upon its outer walls, upon the opposite sides thereof, with longitudinal grooves 3, 35 adapted for the reception of locking strips 4, preferably formed of sheet metal. The side walls are provided between their ends with tongues 5, which project across the grooves 3, and serve to prevent the outward 40 or lateral displacement of the locking strips. At its ends, each locking strip is bent inwardly, as shown at 6, to prevent longitudinal displacement thereof.

Each locking strip is provided with a plurality of V-shaped slits 7, forming a longitudinal row of tongues 8, and these tongues are vertically spaced, as shown.

In the use of the device, with the locking strips 4 in place within the grooves 3, the 50 upper conduit section 2 may be moved longitudinally of the lower conduit section 1, to the desired vertical position, and supported

in this position by bending up a selected pair of tongues 8, so that they engage the lower end of the conduit section.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

1. The combination with inner and outer conduit sections adapted to telescope, the inner conduit section being provided upon its outer side with a longitudinal recess and a pair of retaining tongues projecting partly across the recess and spaced from each other, and a locking strip arranged within the longitudinal recess and held in place by the retaining tongues and having its ends bent over the ends of the inner conduit section, 70 said locking strip having a plurality of vertically spaced tongues stamped therefrom, a selected vertically spaced tongue being adapted to be bent about the lower end of the outer conduit section.

2. The combination with inner and outer conduit sections adapted to telescope, the inner conduit section being provided upon its opposite sides with longitudinal grooves and spaced retaining tongues extending partly across the groove, said tongues being arranged at a point near the central portion of the grooves, sheet metal strips arranged within the grooves and disposed inwardly of said tongues and having their ends bent about the ends of the inner conduit section, 85 said sheet metal strips having holding tongues stamped therefrom, said holding tongues being vertically spaced and adapted to be bent outwardly to engage beneath the 90 lower ends of the outer conduit section.

In testimony that I claim the foregoing as my invention I have affixed my signature in the presence of two witnesses on this 11th day of January, A. D. 1918.

ROBERT A. WALKER.

Witnesses:

G. C. WILLIAMS,
DONALD EVANS.
